APPARATUS FOR SUPPLYING MOLTEN METAL TO MOLDS.

1,195,836.

Specification of Letters Patent. Patented Aug. 22, 1916.

Application filed February 17, 1915. Serial No. 8,845.

To all whom it may concern:

Be it known that we, WILLIAM MONTGOMERY, JR., and JUSTUS RIEHL, citizens of the United States, residing at Baltimore, 5 State of Maryland, have invented certain new and useful Improvements in Apparatus for Supplying Molten Metals to Molds; and we do hereby declare the following to be a full, clear, and exact description of the invention, such as will enable others skilled in the art to which it appertains to make and use the same.

This invention relates to an apparatus for supplying molten metal to molds for use 15 upon type casting machines, and more particularly to a device as specified designed primarily for use upon logotype machines, as disclosed in application for Letters Patent, filed May 15, 1914, Serial No. 838,770.

20 The primary object of this invention is to provide a melting pot which is constructed of a shell having inner and outer spaced walls, and to insert or pack between the inner and outer walls of the melting pot 25 an insulating material for preventing the radiation of heat through the sides of the melting pot, for increasing the heating propclivities of the melting pot and decreasing the amount of fuel necessary for the proper 30 melting of the metal used in casting type bars.

Another object of this invention is to provide an adjustable mounting for a burner for heating the interior of the melting pot, 35 by means of which the distance between the upper end of the burner and the bottom of the melting pot may be varied, as desired.

Another object of this invention is to provide a novel form of pump for forcing 40 molten metal from the melting pot into a casting slot for the forming of "slugs" or type bars.

With the foregoing and other objects in view this invention consists in such novel 45 features of construction, combination and arrangement of parts as will be hereinafter more fully described, illustrated in the accompanying drawings and claimed.

In describing the invention in detail reference will be had to the accompanying 50 drawings wherein like characters designate

like or corresponding parts throughout the several views, and in which:

Figure 1 is a vertical section through the improved melting pot, Fig. 2 is a cross section on the line 2-2 of Fig. 1, Fig. 3 is a fragmentary perspective view of a part of the mechanism for adjustably mounting the burner, Fig. 4 is a side elevation of the pump, and Fig. 5 is a plan view of a part 6a of the actuating mechanism of the pump.

Referring more particularly to the drawings, 1 designates the outer shell or casing of the melting pot, which shell is constructed of inner and outer walls 2 and 3, which are connected at their lower ends by a transversely extending web 4. The inner and outer walls 2 and 3 are spaced from each other, leaving a space 5 between their facing sides, which space is filled with packed "insuloid," which is a non-conductor of heat. The "insuloid" which is packed within the space 5 is formed of treated diatomaceous earth and being a non-conductor of heat will prevent the radiation of the heat 75 from the melting pot and consequently decrease the amount of heat necessary for maintaining the metal within the pot in a molten state.

Diatom is the skeleton of diatomaceous earth which has been treated to remove the organic and foreign substances therefrom.

The inner wall 2 of the melting pot has secured thereto and extending transversely across the interior of the wall, an arcuate bottom 6, which is spaced upwardly from the lower ends of the side walls of the shell 1 and curves upwardly, as is clearly shown in Fig. 1 of the drawings, forming a pocket 7 in the bottom or lower end of the melting pot structure, which receives the heating flame from a burner 8. The burner 8 is of the ordinary construction of burner used upon melting pots, having its upper end 9 flared outwardly for properly spreading the flame issuing therefrom. The burner 8 carries a mixer 10 associated therewith for mixing the proper amount of air with the gas to insure the proper combustion of the latter. A supply pipe 11 communicates with the burner 8 and is provided for supplying the necessary gas to the

- burner. The burner 8 rests upon and is detachably connected to a bar 12, which bar is in turn adjustably carried by vertical bars 13 and 14. The bars 13 and 14 are secured to the under surface of the transversely extending web 4 by means of angled irons 15, and suitable bolts or fastening means 16. The vertical bars 13 and 14 are provided with longitudinally extending slots 17, through which slots extend bolts 18, which are carried by and extend longitudinally from the ends of the bar 12. Thumb nuts 19 are mounted upon the outer ends of the bolts 18 and engage the outer surfaces of the bars 13 and 14, for clamping engagement therewith for holding the bar 12 and consequently the burner 8 in various adjusted positions with respect to the bottom 6 of the melting pot shell 1.
- 20 The melting pot shell 1 has a pipe 20 extending therethrough, which communicates with the interior of the melting pot and has an ordinary stop cock 21 carried by its outer end to permit of the draining of the molten metal from the pot when desired.
- 25 A pump construction 30 is used in connection with the melting pot for supplying the molten metal to a mold, or the casting slot of a logotype or linotype machine.
- 30 The pump construction 30 embodies a body portion 31, which is rectangular in shape and is provided with a well or metal receiving opening 32 extending vertically therein, which has a transversely extending passageway or duct 32' communicating with the bottom or lower end of the same. The passageway 32' also communicates with the lower end of an outlet opening or duct 33.
- 35 The duct 33 extends parallel to the well 32 and into and through a spout 34 which is formed upon the upper end of the body 31. The spout 34 has its upper end tapered, as is shown at 35, and the duct 33 tapers upwardly from the commencement of the taper thereof, being of a smaller diameter at the apex of the spout than otherwise, so as to permit the molten metal, should it become chilled, to fall downwardly within the duct 33. The duct or passageway 33 is of
- 40 uniform bore with the exception of the upper tapered end thereof. The body portion 31 is shorter in length than the width of the interior of the melting pot, and it has transversely extending lugs 36 formed upon the lower end of the same, which lugs engage the inner surfaces of the inner walls 2, and it further has plates 37 formed upon its upper end and extending transversely therefrom oppositely to the direction of the lugs 36, which plates rest upon the upper edges of the walls 2 and 3 of the melting pot shell 1, and also upon the upper surface of transversely extending flanges 39 which are formed adjacent to the upper edges of the outer walls 3. The plates 37

are bolted to the flanges 39' for holding the body 31 of the pump construction 30 properly positioned within the melting pot. The body 31 is provided with a plurality of openings 39 formed therein and extending through the sides of the same, communicating with the well 32, below the upper edge of the same, to permit of the passage of the molten metal into the well.

45 A piston 40 is slidably mounted within the well 32, and has a bar 41 pivotally connected to its upper end, which bar is in turn pivotally connected to a lever 42. The lever 42 is fulcrumed at its outer end as indicated at 43. The lever 42 has an eye 44 formed therein, through which projects a transversely projecting pin 45 upon which is rotatably mounted a roller 46. The roller 46 is provided for engagement with a cam for actuating the lever 42 upon its fulcrum 43 for controlling the movement of the piston 40 within the well 32. The piston 40 is of sufficient weight, to drop, when the lever 42 is released, the cam heretofore mentioned being formed so as to permit of a sudden drop of the piston within the well, for forcing the molten metal upwardly through the duct 33 and out through the upper open end of the same into a casting slot or mold. The openings 39 are formed so as to permit of the flow of the molten metal into the well 32, when the piston 40 is at the upper terminal of its movement. When the piston 40 falls within the well, it automatically cuts off the flow of molten metal into the well, by forming a closure for the openings 39, as is indicated in Fig. 1 of the drawings.

50 If it is so desired, wing nuts may be employed in lieu of the thumb nuts 19, as illustrated in the drawings, without departing from the spirit of this invention.

55 The "insuloid" which is inserted within the space 5 is preferably in a granular state and is firmly packed within the recess. The provision of the "insuloid" within the space between the inner and outer walls of the melting pot will retain the heat generated by the burning gas from the burner 8 within the melting pot and maintain the metal therein in a molten state, for a greater length of time from the use of a minimum amount of heating fuel, than would be possible in the ordinary construction of melting pots. The transversely extending webs 4 form a bottom for the recess 5 and retain the granular "insuloid" within the space 5.

60 From the foregoing description taken in connection with the accompanying drawings the advantages of construction and of the method of operation of the improved apparatus for supplying molten metal to molds will be readily apparent to those skilled in the art to which this invention appertains and, while in the foregoing description, the

principle of the operation of this invention has been described together with various features of construction, it is to be understood that certain minor features of construction, combination and arrangement of parts may be altered to suit practical conditions provided such alterations are comprehended within the scope of what is claimed.

What is claimed is:—

- 10 1. In an apparatus for supplying molten metal to molds, the combination, of a melting pot having spaced inner and outer walls, a web formed integral with and connecting the lower edges of said walls, diatom packed between said walls, means for supplying molten metal to a mold including a body for insertion into the pot, laterally extending wings formed upon the upper end of said body for limiting the insertion of said body into the pot, a spout formed upon and extending upwardly from said body, said body provided with a communicating well and an egress duct, said duct extending upwardly through said spout and gradually decreasing in diameter at the end of the spout, and a piston mounted within said well for forcing molten metal upwardly through said spout.
  - 15 2. In an apparatus for supplying molten metal to molds, a melting pot having inner and outer spaced walls, a web formed integral with and connecting the lower ends of said walls, heat non-conducting material packed between said inner and outer walls, an arcuate web secured to the inner surfaces
  - 20
  - 25
  - 30
  - 35
- of said inner walls upwardly from their lower ends and forming a bottom for the melting pot, a burner for supplying heat to said pot adjustably carried thereby and positioned beneath said web, means carried by said pot for supplying the molten metal to a mold comprising a body having a well and an egress duct formed vertically therein and communicating with each other, a piston slidably mounted in said well for forcing molten metal upwardly through the egress duct upon downward movement of the piston, said egress duct having its upper end tapered inwardly.
3. In an apparatus for supplying molten metal to molds, a melting pot having inner and outer spaced walls, a web formed integral with and connecting the lower edges of said walls, heat non-conducting material packed between said inner and outer walls, an arcuate web secured to the inner surfaces of said inner walls upwardly from their lower ends and forming a bottom for the melting pot, and a drain pipe communicating with the interior of the melting pot a short distance upwardly from said arcuate wall.

In testimony whereof we affix our signatures in presence of two witnesses.

WILLIAM MONTGOMERY, JR.
JUSTUS RIEHL.
